UNITED STATES PATENT OFFICE.

HENRY F. HERMAN, OF NEW YORK, N. Y., ASSIGNOR TO THE IMPERIAL PIANO PLAYER COMPANY, OF NEW YORK, N. Y., A CORPORATION OF NEW YORK.

AUTOMATIC PLAYER FOR MUSICAL INSTRUMENTS.

1,243,169.

Specification of Letters Patent.

Patented Oct. 16, 1917.

Application filed October 11, 1912. Serial No. 725,229.

To all whom it may concern:

Be it known that I, HENRY F. HERMAN, a citizen of the United States, and a resident of the city, county, and State of New York, 5 have invented a new and useful Automatic Player for Musical Instruments, which invention is fully set forth in the following specification.

This invention relates to players for musical instruments having a series of tone-emitting devices which are actuated in accordance with perforations in a music sheet, and relates particularly to electro-magnetically controlled players.

15 It is an object of the invention to provide a player of this character in which the sound-producing devices of a musical instrument are actuated by electromagnets, which magnets magnetically coöperate with a rev- 20 oluble shaft armature common to all the magnets, said magnets being supported independently of but with the pole faces there- 25 of to contact with said armature in a line of contact parallel with the axis of the shaft, and the armature instantly imparting move- 30 ment to the magnets, and immediately actuating the corresponding sound-emitting devices of the instrument, through the mag- netic cling of the magnets to the armature when the magnets are energized.

Another object of the invention is to provide a common motive power to simultaneously advance the music sheet and rotate the armature shaft, whereby a single govern- 35 or may be employed to regulate the advance of the music sheet, and the velocity of the shaft, and thereby the momentum of the blows imparted to the tone-emitting devices.

Other objects and advantages will herein- 40 after appear.

In the drawings accompanying and forming a part of this specification Figure 1 is a front elevation, partly broken away, of a player for musical instruments illustrating 45 an embodiment of my invention.

Fig. 2 is an enlarged sectional side elevation showing an embodiment of my invention applied to the keyboard of a piano, and also illustrating diagrammatically the circuit connections for the electro-magnetically controlled devices.

Fig. 3 is a perspective view of a magnet core employed in connection with my invention.

55 Figs. 4 and 5 are sectional side elevational

views showing modifications of the electro-magnetically actuated means to prolong the sound of a note struck, without using the magnetic cling of the actuating magnet to the armature.

Fig. 6 is a front elevation, partly in section, of a portion of the contact brush.

Fig. 7 is a sectional side elevation of a portion of the tracker-bar with a music sheet passing over the same, and showing the relation of the contact brush thereto; and

Fig. 8 is an elevational view showing an embodiment of my invention applied to the wippen of a piano action.

Similar characters of reference designate 70 like parts throughout the different views of the drawings.

Electro-magnetically operated players for musical instruments as heretofore constructed are complicated and have proven to be 75 more or less impracticable and to have objectionable features, and it is the purpose of the present invention to provide a simple, practical and efficient structure, which is inexpensive and free from complications. 80

The invention may be applied to use in connection with various instruments, to operate directly upon the strings of a piano or parts of a piano action, such as the wippen of the action. However, for convenience an embodiment of the invention has been shown in the drawings and will be described as applied to operate the sound-emitting devices of a piano through the keys of the piano, wherein is employed a perforated music sheet through the perforations in which the desired control is effected of the circuits which include the means for actuating said tone-emitting devices.

In carrying out the embodiment of the 95 invention as shown in the drawings I employ a continuously moving body of such character as to attract a magnet thereto, a revolute iron shaft answering this purpose, and said shaft being rotated in a suitable 100 manner. A plurality of electro-magnets, one for each tone-emitting device of the musical instrument, are supported independently of said shaft and in such relation thereto as to permit the pole faces thereof to contact with said shaft, with the point of contact in a line substantially parallel with the axis of the shaft. The electric circuits or fields of the coils of the electro-magnets to energize the magnets are controlled by and 110

in accordance with the perforations in a music sheet, and each magnet core when energized will magnetically cling to the revoluble shaft, movement being imparted to the magnet by the shaft through said magnetic cling in directions tangential to the surface of the shaft, as determined by the arc of movement of the lever, to actuate a tone-emitting device of the musical instrument, in this instance through a key.

In the embodiment of my invention shown in the drawings the operative mechanism is mounted upon a baseboard 1 having a part 2 to support it upon the piano casing, the 15 tracker bar and music sheet carrying rolls and the advancing means therefor being mounted upon a framework 3 fixed to the baseboard. A take up roll 4 is journaled in the framework 3, and is driven by a spring 20 motor 5 through a shaft 6. A shaft 11 suitably journaled, as in brackets 12, in the framework extends the full length of the keyboard which shaft may be termed the "player shaft" and serves as armature to all 25 of the electro-magnets to attract said magnets when energized. The shaft is rotated in a suitable manner, in the present instance by the spring 5 simultaneously with the take-up roll 4 through a gear 7 fixed to the 30 shaft 6 of the take-up roll meshing with a pinion 9 to which is fixed a gear 8, the latter gear meshing with a pinion 10 on the player shaft. Means are provided to regulate and control the speed of the shaft 11 and of the 35 take-up roll 4, shown as consisting of a governor 13 of the centrifugal ball type, including a friction pad device, driven from the shaft 11. A manually operable control rod or lever 14 co-operates with the friction pad 40 to effect the desired speed control, and also serves to start and stop the operation of the player. By this arrangement there is provided a drive common to both the take-up roll and the shaft 11, and also means to control 45 the speed of said shaft and the advance of the roll.

A contact or tracker-bar 15 is mounted upon the frame 3 between the take-up roll 4 and a roll 16 upon which the music sheet 17 50 is wound, said spool being removably journaled in said frame 3. This tracker-bar is provided with a series of contacts 15' insulated from each other, one for each tone-emitting device, each contact constituting a 55 terminal for the circuit winding or coil of an actuating magnet and alined with a line of perforations in the music sheet. The forward end of the music sheet is adapted to be adjustably connected to the take-up roll 4 in 60 the usual manner, so as to draw the perforated sheet across the face of the tracker-bar.

In front of the tracker-bar is pivotally supported in the frame 3 a metallic brush 65 bar 18 provided with a multiplicity of small

bristle-like wires, which together with the brush bar 18 form a continuous brush common to all the contacts 15', and the bristle-like wires when in position for use bear upon the surface of the perforated music sheet and make contact through the perforations in said sheet with the insulated contacts 15', a number of which wires normally close the circuit through each of the contacts exposed through the perforations in the sheet thereby completing the circuits of the magnet coils. A preferred form of constructing the continuous brush bar to provide a sufficiency of bristle-like wires to insure a contact and completion of a circuit through each perforation in the sheet, however small, is shown in Figs. 6 and 7. In this embodiment bunches or knots 40 of the bristle-like wires are inserted into openings in the brush bar 18 and are held therein by a lacing or wire 41, in the manner used in making an ordinary brush. The wires composing the various bunches diverge upon projecting from the brush bar and combine to form a continuous group representing a full line of fine contacts standing close together, as indicated at 42 (Fig. 6), and having a thickness of a number of wires, as shown at 43 (Fig. 7). As these wires may be of extreme fineness and bear at an angle upon the surface of the music sheet it will be seen that a number of them may penetrate a single perforation in the music sheet, and as one wire is sufficient to make the electric contact the completion of the circuit is assured. It will be obvious that the bristles are held out of contact with the contacts 15' by the music sheet except when one or more of the perforations permit the proper circuits to be closed. The brush bar 18 has a handle 19 to tilt and throw it up away from the tracker-bar 15 when it is desired to insert the music sheet between the brush and tracker-bar.

A conducting bus-bar 21 is mounted upon a pillow block 20 carried by the base 1 and at the rear of the armature shaft 11 to extend the full length of the musical instrument to which one terminal of a suitable source of current, shown as a battery cell or cells 27, is connected through wire 28. The other terminal of the current source is connected through wire 29 to the brush bar 18. A suitable switch 27' may serve, through connections 26, to cut in or out one or more of the battery cells 27.

The bus-bar 21 is preferably of brass of angle shape in cross section, the upright member of which is slotted to receive levers or walking beams 23 pivotally supported by ears 22 alternating with the slots. To the rear end of each lever is pivotally connected a thrust rod 24 to pass through an opening in the base 1 and having a hammer or plunger at the lower end carrying at the end a pad of felt or the like and constituting the

actuator for the corresponding tone-emitting device, in the present instance serving as the actuator for a key. From the front edge of each lever is suspended an electro-magnet 25, each magnet consisting of a box-like frame 25' constituting the core and a coil or winding 25'' surrounding a portion of the core. The electro-magnets are supported independently of but to have contact 5 with the armature shaft 11 with the pole faces of the magnet cores lying sidewise against the peripheral surface of the shaft and contacting with the shaft in a line parallel with the axis of the shaft so that when 10 the electric current is passed through the coil of a magnet by the completion of its circuit, the core of said magnet is energized and instantly magnetically clings to the surface of the shaft and through said magnetic 15 cling is moved endwise with the pole faces of the magnet core lying against the shaft moving in a direction tangential to the surface of the shaft. The movement of the magnet effects the delivery of the required 20 blow to sound the connected sound-emitting device. It will be noted that this movement of the magnet is the result of the magnetic cling of the core of the magnet to the shaft as distinguished from frictional action.

25 It is important that the magnets should not only become energized and sound their notes promptly but also that they should as promptly become deenergized and release the notes in conformity with the perforations in 30 the music sheet. That is, the magnets should be promptly and sensitively and absolutely under the control of the perforations in the music control sheet. Having the magnets in constant contact with the player shaft as 35 their common armature insures that the magnet is in position to instantly sound the note upon the closing of the circuit, because no interval is required to first draw the magnet up to the shaft, with the possibility of 40 producing audible clicks, before the magnet is lifted by the rotating shaft. By thus utilizing the magnetic cling of the magnet core directly against the shaft the instant the circuit of the magnet is opened the cling 45 is destroyed and the parts will be placed in 50 condition to return to their initial position without hindrance.

From the bus-bar 21 the circuit of each magnet coil is completed through its connected walking beam 23, magnet frame or core 25', and thence from the magnet winding or coil 25'', as clearly shown in Fig. 2, and from which coil 25'' the circuit is completed through the wires 29' to a corresponding contact 15' of the contact or track-bar 55 60 65 15'.

To eliminate or relieve any magnetic drag or cling of a magnet to the shaft incidental to prolonging a note through a long perforation in the music sheet, means are pro-

vided to promptly deenergize the magnets when they have accomplished their work of sounding a note, and to otherwise prolong or hold the note as required by the perforation in the music sheet. In Fig. 2 I have shown 70 an arrangement to accomplish this result wherein an auxiliary electro-magnet 30 in series with 25'' is employed, the armature 31 of which magnet is mounted upon the walking beam 23, there being as many magnets 75 30 and armatures 31 as there are keys or walking beams therefor. A short circuit for the magnet 30 is connected to the bus-bar 21 when the walking beam 23 is actuated through the armature 31 carried by said beam coming in contact with the core of said magnet 30, or with a contact piece projecting from or connected electrically to said core. By this arrangement the energization of a magnet coil 25'' effects the actuation of 80 its associated walking beam 23, the actuation of which beam completes the short circuit connection of the holding magnet 30 deenergizing the magnet coil 25'', and causing its core to release its magnetic cling on said 85 shaft 11. By the action of the magnet 30 upon its armature the key is maintained depressed or the note prolonged until the circuit connection of said magnet 30 is again broken through the interposing of the music 90 sheet at the end of the perforation between the contact 15' and the brush bristles 43.

In the modification shown in Fig. 4 the armature 31' is mounted upon the thrust rod 24 to coöperate as hereinbefore described 100 with its holding magnet 30'.

In Fig. 5 a pivoted hook 32 is carried by the walking beam and coöperates with another hook 33 connected to and forming an extension of the armature 34 of the holding magnet 35, the arrangement being such that when the magnet 35 is energized and the walking beam is actuated the hooks 32, 33 engage each other and mechanically retain the beam depressed until the circuit of the 105 magnet 35 is again opened. The magnet 35 is initially energized when the circuit of the coil 25'' is completed thereby positioning the hook 33 in proper relation to be engaged by and to retain the hook 32. The engagement of these hooks completes the short circuit connection around the coil 25'' and through the magnet 35, thereby causing the magnet 25 to become deenergized and holding the walking beam and thrust rod in a 110 depressed position, as before described, until the circuit of the magnet 30 is again opened at the contact 15' when the magnetic parts automatically let go and the magnet 25 returns to normal position.

In Fig. 3 is shown a form of magnet core suitable for use in carrying out my invention, in which construction the core is made from a blank of suitable material bent into box-like shape with perforated ears at the 115 120 125 130

upper end to afford convenient means to suspend it from its associated walking beam 23. The magnet coil is mounted upon the rear side or portion of this frame, as indicated 5 in Fig. 2.

The operation will be readily understood from the foregoing description. The rolled music sheet 16 is properly inserted and the forward end of the perforated sheet 17 10 passed between the contact bar 15 and the brushes 43, the brush bar 18 being lifted to permit the passage of the sheet, the said end then being secured to the take-up roll. The take-up roll and the shaft 11 are then 15 placed in rotation. The unperforated portions of the interposed music sheet support the brushes away from the contacts carried by the contact-bar causing the circuits of the magnet coils 25" to remain open and 20 holding the magnet cores thereof inert. When one or more perforations of the sheet 17 pass over corresponding contacts 15' the circuits of the connected magnet coils 25" are closed by the brushes coming in contact 25 with the contacts 15' uncovered by the perforations, thereby causing the corresponding notes of the instrument to be sounded, the notes struck being prolonged until the limit of the music sheet perforation is 30 reached and an unperforated portion of said sheet is again interposed between the brushes and the contact 15'. The desired modulation is secured by varying the speed of rotation of the shaft 11 through the gov- 35 ernor control rod 14 or by varying the strength of the current in the magnetic circuit through the manipulation of the switch 27. The former changes simultaneously the tempo and the momentum, while the lat- 40 ter varies the power, and hence the momentum of the strokes without affecting the tempo. If desired there may be two batteries one for the bass and one for the treble, or even three or more.

45 In Fig. 8 one form or embodiment of the invention is shown in a diagrammatic manner applied to the interior of a piano, and is operatively connected to the wippen 44 of the piano action. In this construction a 50 series of pivotally supported levers or walking beams 23' are provided from which the electro-magnets are suspended to contact with the revolute armature shaft 11, the ends of the levers engaging below the wip- 55 pen and normally resting upon a support 46, a cushion 47, such as felt or the like, being carried upon the upper side of said support. In operation the shaft is rotated in the direction indicated by the arrow and 60 as a magnet is energized it will be moved upward through the magnetic cling thereof to the shaft raising the lever and thereby the wippen and sounding the note. When the circuit is broken by the music sheet the

magnet will drop to initial position and the 65 lever come to rest upon the support 46.

I have thus described my invention with some particularity of detail, but only for the sake of clearness, since it is not limited to the precise construction and arrangement of parts, but may be provided in various forms and modifications.

Having thus described my invention I claim:—

1. An electro-magnetically controlled 75 player for musical instruments comprising in combination a source of electricity and a plurality of electric branch circuits; a rotatable shaft of magnetizable material; walking beams, electro-magnets including a 80 core substantially of U-shape in cross section and an energizing coil in each branch circuit, each magnet core being suspended from one end of a walking beam with the pole faces contacting with the shaft in a 85 line parallel with the axis of the shaft; means to operatively connect the other ends of the walking beams with the sound-emitting devices of the instrument; and a traveling perforated music sheet to control the 90 making and breaking of the circuits, substantially as and for the purpose specified.

2. An electro-magnetically controlled 95 player for musical instruments having a series of sound-emitting devices, comprising in combination a shaft of magnetizable material rotatable on a horizontal axis; a plurality of electro-magnets, one for each sound-emitting device of the instrument, each magnet including a core substantially 100 of U-shape in cross-section and an energizing coil; means to support the electro-magnets with the pole faces of the cores in position to contact with the shaft in a line parallel with the axis of the shaft and operatively 105 connect the magnets with the sound-emitting devices of the instrument; an electric circuit for each energizing coil; and a perforated music sheet to control said circuits.

3. An electro-magnetically controlled 110 player for musical instruments comprising in combination a rotatable shaft of magnetizable material; pivotally supported walking beams; an electro-magnet substantially of U-shape in cross section suspended 115 from one arm of each walking beam in position with the pole faces thereof to contact with said shaft in a line parallel with the axis of the shaft; an electric circuit for each magnet; a traveling perforated music sheet; and means actuated by each walking beam to cause the sounding of the sound-emitting devices of the instrument.

4. An electro-magnetically controlled 120 player for musical instruments comprising in combination a rotatable shaft of magnetizable material; electro-magnets, each magnet including a core and an energizing

- coil and the core supported with the pole faces contacting with the shaft to have movement imparted thereto through the magnetic cling of the core to the shaft; an electric circuit for each magnet; a perforated music-sheet to control said circuits; and means to short circuit the coil of each magnet substantially as and for the purpose specified.
5. An electro-magnetically controlled player for musical instruments comprising in combination a rotatable shaft of magnetizable material; electro-magnets, each magnet including a core and an energizing coil and the core supported with the pole faces contacting with the shaft to have movement imparted thereto through the magnetic cling of the core to the shaft; an electric circuit for each magnet coil; a perforated music sheet to control the magnet circuits; a second magnet in the circuit of each of the first magnets; a short circuit for each of said first magnets; and means actuated by the first magnets to close said short circuits said second magnets, operating when energized to prolong a note.
6. An electro-magnetically controlled player for musical instruments comprising in combination a traveling perforated music sheet; a revoluble shaft of magnetizable material; means to revolve the shaft and advance the music sheet; a plurality of electric branch circuits controlled by the music sheet; a series of levers; connections between one arm of each lever and the sound-emitting devices of the instrument; an electro-magnet in each of the electric circuits suspended from the other arm of each lever with the pole faces to contact with the shaft in a line parallel with the axis of the shaft and magnetically coacting therewith to have movement imparted thereto; a second magnet in each circuit; a short circuit for each of said first magnets; and means carried by the levers to magnetically coöperate with the second magnets to short circuit the first magnets when the tone-emitting devices have been actuated by the first magnets and hold the levers and the connected tone-emitting devices through the connection therewith to prolong the notes, substantially as and for the purpose specified.
7. An electro-magnetically controlled player for musical instruments comprising in combination a traveling perforated music sheet, and means to actuate the sound-emitting devices of the instrument by and in accordance with the perforations in the music sheet; said means comprising a revoluble shaft of magnetizable material, a motor to simultaneously rotate the shaft and advance the music sheet, levers, one for each sound-emitting device of the instrument, operative connections between one end of each of
- levers and the sound-emitting devices of the instrument; an electro-magnet including a box-shaped core substantially of U-shape in cross section and an energizing coil for the core suspended from the other end of each lever with the pole faces of the cores to contact with the periphery of the shaft in a line parallel with the axis of the shaft, and an electric branch circuit for each magnet controlled by the music sheet, substantially as and for the purpose specified.
8. An electro-magnetically controlled player for musical instruments comprising in combination a traveling perforated music sheet and means to actuate the sound-emitting devices of the instrument by and in accordance with the perforations in said sheet; said means comprising a rotatable shaft of magnetizable material, a motor to simultaneously rotate the shaft and advance the music sheet, a lever for each sound-emitting device operatively connected at one end to a sound-emitting device, an electro-magnet suspended from each lever with the pole faces to contact with the shaft to have movement imparted thereto by the magnetic cling thereof to the shaft, an electric circuit for each magnet the opening and closing of which circuits is controlled by the music sheet, a governor to regulate the movement of the shaft and the travel of the music sheet, and a lever to coöperate with the governor to retard and advance the movement of the shaft and the travel of the music sheet and to start and stop the motor.
9. An electro-magnetically controlled player for musical instruments comprising in combination a rotatable shaft of magnetizable material; actuating electro-magnets, supported independently of the shaft with the pole faces to contact with the shaft; a source of electricity; a branch circuit for each actuating magnet; auxiliary magnets; a short circuit around each actuating magnet; means operated by each actuating magnet to actuate its corresponding sound-emitting device of the instrument and to close its short circuit, said auxiliary magnets when energized operating to hold the sound-emitting devices in actuated position; and a perforated music sheet to control the circuits for the actuating magnets.
10. An electro-magnetically controlled keyboard player comprising in combination a rotatable shaft of magnetizable material; a frame in which said shaft is mounted; a standard disposed adjacent and parallel to said shaft; a bus-bar carried by said standard; levers pivotally supported by and spaced to register said bus-bar with the keys; an electro-magnet having its core connected to one end of each lever with the pole faces of said core to contact with the periphery of said shaft; an energizing coil for each mag-

net core; a source of electricity having a terminal connected to said bus-bar; a contact bar having contacts; a brush common to all the bar contacts; a connection between each contact and one terminal of a corresponding magnet coil, the other terminal of each coil being electrically connected to the other terminal of the source of electricity; a movable perforated music sheet to operate between said brushes and contacts; and

means connected to the other ends of said levers to actuate the keys.

In testimony whereof I have signed this specification in the presence of two subscribing witnesses.

HENRY F. HERMAN.
